UNITED STATES PATENT OFFICE.

LAWRENCE MOORE LEA, OF HATTIESBURG, MISSISSIPPI, ASSIGNOR TO ADRIAN K. McINNIS, OF HATTIESBURG, MISSISSIPPI.

LETTER-TIE.

1,324,424.

Specification of Letters Patent.

Patented Dec. 9, 1919.

Application filed November 7, 1917, Serial No. 200,783. Renewed May 10, 1919. Serial No. 296,106.

To all whom it may concern:

Be it known that I, LAWRENCE M. LEA, a citizen of the United States, residing at Hattiesburg, in the county of Forrest and 5 State of Mississippi, have invented new and useful Improvements in Letter-Ties, of which the following is a specification.

This invention relates to new and useful improvements in package ties, and the principal object of the invention is to provide a device of this nature whereby the tension on the cord tends to make the grip on the cord more secure.

Another object of the invention is to provide the device with a hook at one end about which the cord is passed with a half hitch and which will permit the cord to be tightened around the package by simply pulling on its free end, and which may be untied by pulling the end upwardly in an opposite direction.

Another object of the invention is to provide a device of this character which is simple and durable in construction, reliable 25 and efficient in operation and one which can be manufactured and placed upon the market at a minimum cost.

The invention also consists in certain other features of construction and in the 30 combination and arrangement of the several parts, to be hereinafter fully described, illustrated in the accompanying drawings and specifically pointed out in the appended claims.

35 In describing my invention in detail, reference will be had to the accompanying drawings wherein like characters denote like or corresponding parts throughout the several views and in which:—

40 Figure 1 is a perspective view of the device.

Figs. 2 and 3 are perspective views illustrating the successive steps in the operation of securing a package by the device.

45 Fig. 4 is a like view showing how the package is untied.

In these figures 1 represents the locking member which is preferably formed of metal or the like and is provided with an enlarged 50 head 2 having an opening 3 therein and also a small opening 4 slightly below said opening 3 and to one side of the longitudinal center of the device. Below the head the

device tapers slightly toward the other end and at this end it is provided with a hook 55 5, and opposite the hook the metal is bent upwardly at right angles to form a lug 6. The upper edge of said lug extends perpendicular, while the other edge tapers off gradually to the end of the device. 60

The string 7 is passed through the hole 4 and the end knotted to secure it therein. The cord is then wrapped around the package to be tied and the end passed over the hooked end in engagement with the edge 65 of the lug and is then brought back and passed through the hook and drawn tight. It will be seen that the cord is passed around the hooked end in a half hitch so that the tension of the cord around the package prevents the free end of the cord from slipping. In carrying out these operations the device is held in proper position by the thumb engaging the enlarged head of the device. When it is desired to untie the 70 75 package it is simply necessary to pull upwardly on the free end of the cord, as shown in Fig. 4 to release the string from the hook.

It is thought from the foregoing description that the advantages and novel features of my invention will be readily apparent. 80

I desire it to be understood that I may make slight changes in the construction and in the combination and arrangement 85 of the several parts, provided that such changes fall within the scope of the appended claims.

What I claim is:—

1. A device of the class described comprising 90 a flat metal strip having a hook at one edge at one end thereof, an upwardly extending lug on the opposite edge, and an enlargement at the other end.

2. A device of the class described comprising 95 a member made of a flat piece of metal and having an enlarged head having an opening therein and a second opening adjacent said first mentioned opening adapted to receive the end of a string, a hook at 100 the other end of said device, and projecting upwardly from one edge thereof, and an upwardly extending lug opposite said hook.

In testimony whereof I affix my signature.

LAWRENCE MOORE LEA.

It is hereby certified that Letters Patent No. 1,324,424, granted December 9, 1919, upon the application of Lawrence Moore Lea, of Hattiesburg, Mississippi, for an improvement in "Letter-Ties," were erroneously issued to Adrian K. McInnis, as assignee of the entire interest in said invention, whereas said Letters Patent should have been issued to the inventor, said *Lea*, and *Adrian K. McInnis*, said McInnis being assignee of *one-half* interest only in said invention, as shown by the record of assignments in this office; and that the said Letters Patent should be read with this correction therein that the same may conform to the record of the case in the Patent Office.

Signed and sealed this 20th day of January, A. D., 1920

[SEAL.]

M. H. COULSTON,

Acting Commissioner of Patents.
